UNITED STATES PATENT OFFICE.

JOHN A. JACKSON, OF CHESTERTON, INDIANA, ASSIGNOR, BY DIRECT AND MESNE ASSIGNMENTS, TO THE RYAN CAR COMPANY, OF CHICAGO, ILLINOIS, A CORPORATION OF MAINE.

FLUID-PRESSURE HAMMER.

Application filed December 28, 1917. Serial No. 209,278.

To all whom it may concern:

Be it known that I, JOHN A. JACKSON, a citizen of the United States, and a resident of Chesterton, in the county of Lake and 5 State of Indiana, have invented certain new and useful Improvements in Fluid-Pressure Hammers, of which the following is a specification.

The present invention relates in general 10 to fluid pressure actuated forming devices, and more particularly to that class of devices commonly termed pneumatic hammers, and more specifically to the class of such devices which carries a removable tool. 15 The principal objects of my present invention are the provision of a structure of the nature referred to which may be constructed, for the most part, from standard material readily to be obtained in the 20 market, one wherein are employed a minimum number of special castings and specially machined parts, one which may be easily constructed in any ordinary machine shop equipped with a drill-press and common 25 metal cutting tools, and one which does not require for production any elaborate grinding, milling, or other metal-shaping machinery; the provision in a device of the character described, of means whereby the movement of the hammer, chisel, cutter or other 30 tool employed may be kept under the absolute control of the operator; the provision of improved means for absorbing shock in the event that the tool is knocked out of the 35 tool holder or displaced therefrom, the provision of improved means for operating fluid pressure actuated tools, the provision in a tool so characterized of improved manual operating means, together with such 40 other objects as may hereinafter appear.

While one of the principal uses of the device has been its employment alternately as a deheader for rivets, or as a sheet cutter, obviously it has a wide range of utility 45 for other purposes according to the character of tool employed therewith.

In attaining the objects mentioned and gaining certain further benefits and advantages to be below disclosed, I have provided 50 a structure, one embodiment whereof is illustrated in the accompanying drawings wherein—

Figure 1 is a longitudinal elevational

view of a construction embodying my present improvements;

55

Figure 1^a is an elevational view of a detail of construction;

60

Figure 2 is a longitudinal sectional elevational view of the right-hand portion of the structure shown in Figure 1;

65

Figure 3 is a similar longitudinal sectional elevational view of the left-hand portion of the structure of Figure 1; and

Figures 4 and 5 are sectional views taken 65 on the lines 4—4 and 5—5 of Figure 2, looking in the directions indicated by the arrows.

Referring now more particularly to Figure 1, it will be seen that I have here shown in elevation a general assembly view of a 70 structure embodying my present improvements, wherein I conveniently employ a main casing 10 within which the free piston-hammer 24 reciprocates; a fluid pressure supply pipe comprising portions 11 and 11^a 75 for applying pressure alternately to opposite ends 10^x and 10^y of the casing 10 for operating the hammer; a holder 12, having a thickened portion 12^x having an opening 12^x within which the tool reciprocates, such 80 holder forming a guide for the shank of the tool and also containing a mechanical shock absorber to be below referred to, and having a passage 14^x within which is mounted the elbow 14, which is part of the supply pipe 85 11; and at the opposite end of the casing a return or U-connection 15, which holds the other end of the supply pipe in place.

At some convenient point in the supply pipe 11 I dispose valve casing 17 provided 90 with a control valve 16 operable by a handle 16^a.

For absorbing vibration and thereby preventing crystallization and breakage the supply line 11 is preferably furnished with a 95 piece of flexible hose 18 connected to the elbow 14, and to a nipple 19, by means of clamps 20, 20^a.

The employment of the connecting hose 18, not only serves to absorb any tendency 100 towards vibration with consequent crystallization and breakage, between the members 10 and 11, but also simplifies construction inasmuch as it avoids the use of "union connection," which might otherwise be required.

105

A clamp 21 also engages the casing 10 and the pipe line 11 for holding these two elements of construction in predetermined parallel relation. Fluid under pressure is supplied to the pipe 11 from any convenient source, preferably a flexible hose (not shown) attached to one end of a goose-neck or inverted U-shaped pipe, having one leg downwardly disposed in substantial parallelism to the members 10 and 11 in order to prevent kinking of the supply hose.

Referring now more particularly to Figure 2, it will be observed that the tool holder 12 has threaded engagement as indicated at 15 12^a with the pipe 10, a pin 10^a being employed for holding the parts 10 and 12 in predetermined relation.

Within the tool holder 12 I arrange within a socket or recess 25 a yieldingly resistant device, preferably a helically coiled spring 26, held in position by a collar 26^a, which, in turn, abuts against the end of the casing 10 under the pressure of the spring 26. The parts 26 and 26^a are arranged to permit the passage of the tool-shank 23^a therethrough and so as to absorb shock of the piston 24 in case pressure should be admitted to the pipe 11, either when the tool 23 is not in place or when the tool 23 has no resistance at its outer end and so would be knocked out of place by the hammer 24.

One or more atmospheric vents 27 are employed for relieving pressure in front of the piston as it moves towards the tool 23 35 and delivers the blow upon such tool. The vent or vents 27 are so proportioned and positioned relatively to the length of the piston hammer 24 and of the casing 10 as afford such an amount of cushioning effect 40 as may be desirable in the traverse of the piston 24 towards the right-hand end of the device, as shown in Figure 2.

Referring now more particularly to Figure 3, it will be observed that the connecting member 15 between the casing 10 and the portion 11^a of the air pipe 11 has threaded engagement with the casing 10, as indicated at 15^a, and with the pipe portion 11^a, as indicated at 15^b, a pin 10^b being employed to 50 hold the parts 10 and 15 in predetermined relation.

The operating valve may conveniently comprise a casing 17 containing a plug valve 16, which is provided with a passage 16^b adapted alternately to place the pipes 11 and 22 in communication, when the handle 16^a is in the position indicated in the drawings, and to place the pipes 11^a and 22 in position when the handle is moved to the 60 left of its position shown in Figure 1 through an arc of 90°.

The valve casing 17 is also provided with an atmospheric exhaust port 28 and the plug 16 with a passage 16^c adapted to put the 65 pipe 11^a and such exhaust port 28 in com-

munication when the handle 16^a is in the position indicated in Figure 1 of the drawings, and the pipe 11 and the exhaust port 28 in communication when the handle 16 is moved to the right into a position at a right angle 70 to that shown in Figure 1.

It will be noted on examination of Figures 3, 4 and 5, that the piston hammer 24 has two heads, as indicated at 24^a and 24^b and that the device is reversible in case the 75 head 24^a becomes expanded by striking the shank 23^a of the tool 23.

In the operation of the structure above described, it will be apparent that when the parts are in the position shown in the drawings, fluid pressure admitted through the U-connection 22 passes through the passage 16^b in the valve 16 and thence through the pipe 11, nipple 19, hose connection 18, elbow 14, port 14^x into the right-hand end 10^x of the casing 10, and thence against the head 24^a of the piston hammer 24, forcing the piston toward the left-hand end 10^y of the casing 10, the piston in its traverse to the left uncovering the ports 27 and establishing 80 communication with the atmosphere.

As the piston begins the movement to the left, the handle 16^a of the valve 16 is moved across vertical (lap) position into a position at a right angle to that shown in Figure 1. 95 This establishes communication between the pipe 22, the passage 16^b, the pipe 11^a, the passage 15^x, thereby admitting fluid under pressure into the left-hand 10^y of the casing 10 and against the head 24^b of the piston 100 24, which causes the piston 24 to move to the right and strike against the end of the shank 23^a, when such tool is in position, and if the tool is not in position the head 24^a will strike against the collar 26^a and the 105 shock will be absorbed by the spring 26.

From the foregoing description it will be apparent that as the piston moves from the end 10^y of the casing 10 toward the tool 23 at the end 10^x of such casing any fluid 110 between the end 10^x and the atmospheric vent 27 will be discharged to the atmosphere through such port, and the fluid between the ports 27 and the port 28 will be discharged to the atmosphere through such port 28. On the other hand, when the piston 24 is moving from the end 10^x of the casing, toward the end 10^y thereof, on the return stroke, any fluid contained between the head 24^b of the piston and the valve 16, 115 is discharged to the atmosphere through the exhaust port 28.

From an examination of the elements of construction entering into the structure of my improved fluid pressure tool, it will be observed that substantially all parts, save the connecting members 12 and 15, are readily to be obtained on the market and assembled without the use of special tools or machinery, and likewise such connectors 120 130

12 and 15 can be purchased at relatively little expense.

It will further be observed that where a manually operated valve, such as is herein disclosed, is employed, the movement of the piston, either on striking or return stroke, is entirely under the will of the operator, and therefore, the action of the tool employed may be governed with great nicety. Furthermore that the movement may be as slow or rapid as desired, depending upon the rate of oscillation of the handle 16^a.

Having thus described my invention and illustrated its use, what I claim as new and desire to secure by Letters Patent is:

A device of the character described, comprising, in combination, a main casing, a piston hammer reciprocable in said casing, an external fluid supply pipe for applying fluid to opposite ends of said hammer, a

valve device for alternately establishing communication first with one end and then with the opposite end of said hammer, a tool-holder casing carried by the casing and having a portion adapted to receive and guide the shank of a tool operable by said hammer, a shock-absorber disposed in said second casing between the tool-holder portion thereof and said main casing and independently of said tool shank, and a shock absorber element in said fluid supply pipe, said fluid supply pipe being connected adjacent the end of the main casing opposite to said tool-holder casing, and to said tool-holder casing intermediate said main casing and the tool guide portions thereof.

In testimony whereof, I have hereunto signed my name.

JOHN A. JACKSON.
